GEORGE I. NEWMAN AND LAWRENCE A. NEW, OF CHICAGO, ILLINOIS, ASSIGNEES TO
UNITED SPRING CORPORATION, OF CHICAGO, ILLINOIS, A CORPORATION OF
ILLINOIS

SPRING CONSTRUCTION

Application filed May 14, 1928. Serial No. 277,417.

This invention relates to mattress and upholstery springs, more particularly, of the type in which the spring units are of a general oblate spheroidal form. It has been proposed to construct spring units of this shape from a series of elliptical wires or clock spring steel strips symmetrically arranged about a central axis and provided with a restraining ring secured to the peripheral portions of such wires or strips so that downward pressure on such units cannot extend such peripheral portions laterally.

In such construction the strips have been riveted together where they cross each other so that the springs are held in the desired angular relationship with respect to each other by friction alone.

Further the retaining ring was secured to the strips by clips which were held in place on the ring by friction.

In practice it has been found that this frictional engagement is insufficient to maintain the springs in proper angular relationship.

The principal object, therefore, of the present invention is to provide means for positively retaining the spring strips in proper angular relationship.

Other and further important objects of this invention will be apparent from the disclosures in the accompanying drawings and the following specification.

The invention (in a preferred form) is illustrated in the drawings and hereinafter more fully described.

On the drawings:

Figure 1 is a plan view of a spring unit constructed in accordance with the present invention.

Figure 2 is a perspective view of the central spacing member.

Figure 3 is a section on the line III—III of Figure 1.

Figure 4 is a perspective view of one of the retaining ring clamps and adjacent portions of the ring.

Figure 5 is a section on the line V—V of Figure 4.

Figure 6 is a plan view of the retaining ring and adjacent parts of adjoining rings and outer frame.

Figure 7 is a section through one of the clamps connecting one of the retaining rings to the outer frame.

Figure 8 is a section on the line VIII—VIII of Figure 7.

Figure 9 is a section on the line IX—IX of Figure 7.

As shown on the drawings:

The spring units are formed of four strips of clock spring steel 1 bent into circular form 60 so that their ends overlap. The overlapping ends of all the four strips are riveted together at 2 as are also the diametrically opposite portions of the strips where they cross each other.

These clock spring circles are arranged at about 45° from each other so that they are symmetrically arranged with respect the vertical axis of the unit passing through the upper and lower rivets. To retain the springs 70 in proper angular relationship spacing members 3 are provided which are of sheet metal slit along radial lines with the margins of each slit turned over to form arms 4 having inwardly directed flanges 5 along each side. 75 These flanges engage the sides of the spring strips 1, as shown in Figure 3, and positively prevent any change in the relative positions of the spring strips. The same rivets 2 which hold the spring strips together also clamp 80 the spacing members 3 to the strips.

The flattened or oblate spheroidal form is produced by spreading the spring circles laterally by means of a peripherally arranged wire ring 6 which is clamped to the spring strips by clips or connectors 7 (Figure 4). These clips are stamped of sheet metal and consist of a centrally located tab 8 bent over the ring 6, laterally extending wings 9 adapted to be bent around the margins of the adjacent spring strip and upwardly and downwardly extending wings 10. The latter are curved inwardly somewhat and are provided for the purpose of preventing the spring strips being bent beyond their elastic limit 95 at their point of greatest flexure, viz; where they contact with the peripheral wire 6. To prevent the clips 7 sliding along the wires 6 the portions of the wires 6 engaged thereby are offset so that shoulders or bends 11 in the 100

wire are formed on either side of the encircling tabs 8.

The spring units in a complete mattress are connected together where the peripheral wires 6 of adjacent units contact as indicated in Figure 6. At the points of connection the wires 6 are offset at 15 to prevent sliding movement of the wires relatively to the connecting bands or clips, which may be similar in construction to that shown in Figure 9.

Around the outer margin of the spring assembly is an outer wire frame 11 clamped to the peripheral wires 6 by bands or clips 12. The ends of each of the wires 6 may be connected by bending the tips inwardly and encircling them with bands or clips 13.

We are aware that many changes may be made, and numerous details of construction may be varied through a wide range without departing from the principles of this invention, and we therefore do not purpose limiting the patent granted hereon, otherwise than necessitated by the prior art.

We claim as our invention:

1. A spring unit comprising a plurality of elliptical spring steel strips having overlapping ends and a common vertical axis where the ends overlap, a central spacing member, a rivet on said axis clamping the overlapping ends of the strips together and to said spacing member, and radially extending arms on said spacing member having downwardly extending flanges engaging the sides of each of the spring steel strips to maintain a fixed angular relationship therebetween.

2. A spring unit comprising a plurality of elliptical spring members having overlapping ends and a common vertical axis where the ends overlap, a peripherally arranged ring, and clips securing said members to said ring to prevent lateral outward movement of the peripheral portions of said members, the portions of the ring adjacent the clips being bent to form shoulders for holding the clips in position on the ring.

3. A spring unit comprising a central spacing member and a plurality of spring strips having overlapping ends fastened to said central spacing member by a single fastening member, said spacing member having radial arms, downwardly extending flanges on said arms engaging the sides of said spring members, a peripheral ring, clips connecting the ring and the spring members, and said ring having shoulders thereon to prevent movement of said clips along the same.

4. A spring unit comprising a plurality of separate elliptical spring steel strips disposed about a common vertical axis, the ends of said strips being overlapped, a spacing member engaging the ends of said strips, means for securing the ends of said strips to said member, and a peripheral ring connected to said strips, said ring and member conjointly main-

taining said strips in fixed angular relationship.

5. In a spring unit, a plurality of spring steel strips disposed about a common vertical axis, a peripherally arranged ring having an offset portion adjacent each strip, and a plate member lying between each strip and offset portion of the ring, said plate having outwardly extending wings for bending around the strip and an inwardly turned tab for bending around the offset portion of said ring.

6. A spring unit comprising a plurality of separate elliptical spring steel strips disposed about a common vertical axis, the ends of said strips being overlapped, a central spacer plate having radially extending grooves open on their under side for receiving the end portions of said strips, said grooves restraining said strips against relative angular movement, and means for securing said spacer plate and overlapped ends together.

In testimony whereof, we have hereunto subscribed our names.

GEORGE I. NEWMAN.
